PACKING MACHINE

Verne W. Gordon, San Jose, Calif., assignor to
Dante H. Giannini, San Jose, Calif.

Application March 18, 1937, Serial No. 131,645

2 Claims. (Cl. 226—14)

The present invention relates particularly to a machine for packing lettuce and the like in suitable crates or containers.

Selecting lettuce as an example of the type of material to be packed by the machine, its character should be carefully noted. When the lettuce reaches the hands of the packers it is quite a solid compact head, the trimmers having removed the outer and looser leaves as a part of the trimming process. Even so, the heads must be packed in solid layers under considerable compression to allow for any shrinkage or other adjustments that might take place during shipment. This packing by hand is a laborious process and an expensive one.

It is one object of the present invention therefore, to provide a machine so constructed and arranged that it will pack the lettuce heads in the crate without injury thereto, and yet so compactly that they can be shipped long distances without danger of relative movement in the crate.

In the drawings:

Figure 1 is a side elevation of a machine embodying my invention.

Figure 2 is a sectional view on line 2—2 of Figure 1.

Figure 3 is a diagrammatical illustration of the method of operation of the machine.

Figure 4 is a sectional detail view on line 4—4 of Figure 2.

Figure 5 is a detail illustration of another embodiment of a portion of the machine.

Figure 6 is a detail illustration of the method of mounting some of the pressure plates.

In the particular embodiment of the machine herein disclosed, I show at 1 an upright rectangular framework in which is mounted a vertically slidable cage as 2. The vertical movement of the cage 2 is controlled by air pressure through the medium of cylinder 3 mounted on frame 1 and its piston 4 connected to the cage 2, the air conduits through which air is moved to actuate the piston in either direction showing in part at 5.

At 6 is shown a cap member having a substantially convex form and adapted to seat upon the top of a layer of lettuce heads. This cap is carried by two vertical rods 7 mounted for vertical movement in frame or cage 2 and mounted in a cross bar 8. To the cross bar 8 is connected a piston 9 operating in a cylinder 10 on cage 2. The movement of the piston and cap is controlled by air pressure introduced into the cylinder 10 at 11.

Encompassing the cap 6 are four pressure

plates as shown at 12, 12a, 12b, 12c, these four plates being mounted and operated in the same manner and at the same time, and identical in construction. The plates 12, 12b are supported by arms as 13, 13b, pivotally mounted on cage 2 as at 14, and normally lie in spaced relation to cap 6.

Since these pressure plates must be moved positively and at desired intervals of time toward and away from the cap member 6 the following mechanism is provided.

A cylinder 15 is mounted on the cage 2 and supplied with air under pressure at 16, to operate a piston 17. The piston 17 carries a horizontal plate 18 to which are connected rods 19, 19b, these rods being pivotally connected to the plate and to their respective pressure plates 12 and 12b.

The pressure plates 12a and 12c are mounted and operated in the same manner as plates 12 and 12b, and consequently similar parts are designated by similar numerals followed by appropriate letters. The arms 13a and 13c are mounted on bars as 20 rotatably mounted on cage 2.

The result of the construction described is that the four pressure plates normally assume the positions shown in Figure 1 in spaced relation to cap 6, but when the air pressure is applied to move piston 17 upwardly, then the rods 19 to 19c draw the said pressure plates inwardly until they contact the edges of cap 6.

The corner pressure plates 21 to 21c are mounted on arms 22 to 22c pivotally mounted on cage 2 as at 23 to 23c. These corner plates are moved simultaneously with the side plates 35 through the medium of rods as 24 to 24c connected to plate 18, these plates completing a contractable rectangular gripping structure for compressing the lettuce heads beneath cap 6.

It is obvious that any suitable source of air pressure may be utilized, and the air pressure may be controlled by suitable conduits and valves not shown.

To properly position the lettuce heads so they may be grasped and lifted in a body by the above described machine I provide a pan 25 of such size that the pressure plates will fit snugly within its four sides when fully extended. The pan has a slightly conical bottom as indicated at 26.

In preparing the lettuce for packing, the heads 50 are placed side-by-side in the pan, by hand, until the pan is filled. The pan is then centered under the cage 2 as shown and the cage lowered to insert the pressure plates as described. In this operation the cap 6 contacts the tops of the under- 55

lying heads of lettuce and is pushed up thereby. When the plates are in position the piston 17 is operated to draw the plates centrally until they contact the edges of the cap 6, thereby compressing 5 the lettuce heads into the limits defined by the edges of the cap. The cage 2 is now raised and the compacted lettuce lifted above the top level of the pan.

A crate 21 having been placed immediately 10 below the pan, the pan is now removed and the cage lowered until the pressure plates reach the bottom of the crate. The piston 17 is now again operated to spread the pressure plates to the 15 walls of the crate, and the piston 9 is operated to press down the center of the layer of heads which now expand to cover the bottom of the crate.

After the bottom layer is placed in position the cage is raised and the same sequence of 20 operations is repeated for each successive layers 20 of heads deposited in the crate.

In the diagram, Figure 3, are shown three 25 positions of the crate loading mechanism. At A the several parts are shown in the starting position. At E the same parts are shown as they appear when lowered to the pan 25 and operated to compress the lettuce under the cap 6. At C the same parts are shown after they have been raised to the starting position A, the pan 30 removed, and then lowered to the bottom of the crate 21.

When the lettuce heads are placed in the pan 25 the side rows will, of course, contact the sides of the pan, with the result that when the pressure plates are lowered into the pan they contact 35 the sides of those heads and tend to turn them out of their upright positions.

To positively hold the heads in position while the pressure plates are being lowered I provide 40 vertically sliding rods as 28 in guides as 29 on the inner side of each plate. These rods carry foot plates as 30 adapted to seat on the lettuce heads and urged into said contact by springs as 31.

The lettuce heads may be held out of contact 45 with the walls of the pan by a guard comprising

a bar as 32 supported against the inside of the pan sides by spring members as 33 on each end thereof and passing down through the bottom of the pan and inwardly along its bottom and secured thereto as at 34. The bar 32 also carries depending pins as 35 reciprocating through holes as 36 in the bottom of the pan. When this device is used the descending pressure plates rest upon the bars 32 and press the same downwardly as they pass between the heads and the 10 pan walls.

It is to be understood, of course, that while I have herein shown and described but one specific embodiment of the invention, changes in form, construction, and method of assembly and operation may be made within the scope of the appended claims.

I claim:

1. The method of packing lettuce and the like in a crate which consists in arranging a layer of 20 heads in a loosely compact formation inclined 20 upwardly to the center from all sides to cover an area of the same shape but of greater dimensions than the crate, supporting the central portion against upward displacement, compressing 25 the layer laterally into lesser dimensions than the crate, depositing the compressed layer in the 30 crate, releasing the same to expand to the dimensions of the crate, and pressing down the central portion to the level of the sides of the layer. 30

2. A packing machine for head lettuce and the like comprising, a pan having a bottom upwardly inclined toward the center from all sides and adapted to receive a layer of heads of lettuce, a presser cap member of lesser dimensions than 35 the pan engageable with the top of the central portion of the layer and actuating means therefor, compressor members movable into the pan to engage the side heads, power actuated means 40 associated with the members to move them inwardly of the pan and compress the layer beneath said cap, and means for simultaneously moving the cap and members vertically to lift the compressed layer out of the pan. 40
